UNITED STATES PATENT OFFICE.

JOSEPH A. CLIFFORD, OF WASHINGTON, DISTRICT OF COLUMBIA.

ELECTRICAL LAMP.

1,405,287.

Specification of Letters Patent. Patented Jan. 31, 1922.

Application filed January 21, 1921. Serial No. 438,908.

To all whom it may concern:

Be it known that I, JOSEPH A. CLIFFORD, a resident of Washington, in the District of Columbia, and a citizen of the United States, 5 have invented certain new and useful Improvements in Electrical Lamps, of which the following is a specification.

This invention relates, generally, to theatrical appliances and, particularly, to devices for illuminating theatre-stages; and has for its object to provide a novel construction of portable, floor-supported electric lamp having a resiliently-supported, lamp-bulb casing, whereby the tendency to 15 break of the tungsten filaments of the lamp is obviated.

It will be understood that portable stage-lamps are heavy and are subjected to somewhat rough handling by theatre-employes, 20 in being dragged from place to place on the stage, the ensuing jars and vibrations tending to break the tungsten filaments of the lamp, if the lamp-supporting pedestal is a rigid structure.

Other objects, going to make up the ultimate perfection of the lamp as an entirety, will appear as the specification proceeds and the nature of the invention is more fully understood.

The invention is clearly illustrated in the accompanying drawing, forming part of my specification, and in which like reference characters indicate corresponding parts in the two views. Briefly described:

Figure 1 is a view in perspective of a stage-lamp constructed in accordance with my invention, and

Figure 2 is a fragmentary view in side elevation, partly in section, of the lamp.

In the illustrated embodiment, 1 is a suitable base, which, as shown, is preferably a disk-shaped member, having a central upwardly-standing boss 2, in which is screwed or otherwise suitably secured a pedestal 3, which 45 may, as shown in Fig. 2, be a tubular member and may be exteriorly threaded, toward its upper end, for engagement with the internally-threaded portion of a nipple 4.

Telescoping in said pedestal 3 is a stem 5, 50 preferably tubular, carrying, at its top, a bracket 6 having a bracket-arm 7 provided, laterally, with a yoke 8 to receive a bar 9 depending from a lamp-casing 10 and pivoted thereto, as at 11. A set-screw 12 carried by the yoke 8 and bearing against the bar 9 holds the latter against movement,

when the lamp-casing 10 has been tiltably adjusted to the desired position.

The lamp-casing 10 is tiltably supported upon the bracket, by being pivoted thereto, 60 as shown at 13.

The lamp-casing 10 carries therein the lamp bulb 14, to which is connected the electric circuit wiring in the cable 15.

To cushion the lamp-casing 10 and thus 65 the tungsten filaments in the lamp-bulb 14 against shocks and jars, incident to pulling the portable lamp about the stage, I provide the means about to be described. A coiled spring 16 encircles the stem 5 and bears, at 70 its upper end, against a collar 17 adjustably secured to the stem 5 by means of a set-screw 18; and, at its lower end, against the looped terminal 19 of a wire hook 20 supporting the cable 15, which passes through 75 an eye 21 carried by the pedestal 3, toward the lower end thereof. The looped terminal 19 of the hook 20 encircles, as shown, the stem 5, and bears upon the upper end of the nipple 4, and is yieldingly held against upward displacement, or swinging movement 80 on the rod 5 as a pivot, by the spring 16. The spring, therefore, in the peculiar combination of parts described, serves two functions,—namely, constitutes a common means for resiliently supporting the rod or stem 5 and thus cushioning the lamp-filaments against shock, and for frictionally holding the hook 20 in any position of rotative adjustment and also yieldingly holding the 85 hook against upward displacement. By raising or lowering the collar 17 on the stem 5, the degree of projection of the latter within the pedestal 3 may be varied, as desired.

It will be seen that, by the peculiar construction provided, all jars and shocks, incident to moving the lamp about the stage, will be taken up, and the lamp-casing 10 cushioned against shocks and jars, and the tungsten filaments of the electric-light bulb 90 14 will not be broken by such shocks and jars.

It will be seen also, that the means for cushioning the lamp-casing 10 necessarily, in my construction, comprehends three elements, namely, the slideable stem 5, the collar 105 17, and the spring 16, since these three elements are indispensable and enter into combination in cushioning the lamp-casing 10. It will also be seen that by adjusting the collar 17 lengthwise on the stem 5, the projection of the latter within the pedestal 3 110 may be varied, whereby the lamp-casing 10

may be disposed nearer to or farther from the stage or floor.

Having thus fully described my invention, what I claim as new and desire to secure by 5 Letters Patent of the United States is:

A portable electric lamp, comprising a hollow pedestal, a lamp-casing for the electric-light bulb, a stem telescoping in said pedestal and supporting said lamp-casing, a 10 cable enclosing the electric wire-conductors, a wire cable-supporting hook having a looped terminal encircling said stem and resting upon the top of said pedestal, and common means for resiliently supporting

said stem in said pedestal, and for holding 15 said hook in any position of rotative adjustment and also yieldingly holding said hook against upward displacement, said means comprising a coiled spring encircling said stem and bearing, at one end thereof, against 20 said looped terminal of said hook, and a collar carried by and adjustable longitudinally of said stem and bearing against said coiled spring at the other end thereof.

In testimony whereof, I hereunto affix my 25 signature.

JOSEPH A. CLIFFORD.
